UNITED STATES PATENT OFFICE.

LEE DE FOREST, OF NEW YORK, N. Y., ASSIGNOR TO DE FOREST RADIO TELEPHONE AND TELEGRAPH COMPANY, OF NEW YORK, N. Y., A CORPORATION OF DELAWARE.

METALLIC AUDION.

1,230,874.

Specification of Letters Patent. Patented June 26, 1917.

Application filed February 21, 1917. Serial No. 150,027.

To all whom it may concern:

Be it known that I, LEE DE FOREST, a citizen of the United States, residing at New York, in the county and State of New York, have made a certain new and useful 5 Invention in Metallic Audions, of which the following is a specification.

This invention relates to audions.

The object of the invention is to provide 10 an audion which is simple in structure and which will allow rough handling without the danger of breakage in shipment and in use.

A further object of the invention is to 15 provide an audion with a metal shell which shell will form one electrode of the device.

Further objects of the invention will appear more fully hereinafter.

The invention consists substantially in 20 the construction, combination, location and relative arrangement of parts, all as will be more fully hereinafter set forth, as shown in the accompanying drawing, and finally pointed out in the appended claims.

25 Referring to the drawing:—

Figure 1 is a view in vertical section of an audion embodying my invention.

Fig. 2 is a similar view of a modified structure embodying my invention.

30 The same part is designated by the same reference numeral wherever it occurs throughout the several views.

The commercial form of audion used as 35 an oscillation generator and known as an oscillion now on the market comprises an evacuated glass vessel of various shapes, with the electrodes of the audion sealed there through in the usual way. These glass audions are necessarily fragile, and in con- 40 sequence require great care in handling and shipping the same.

It is among the special purposes of my 45 present invention to provide an audion which can stand a lot of abuse in handling and shipping the same without the danger of breakage.

In accordance with my invention I provide 50 a metal flask 1 open at one end and provided with a restricted neck 2 at the other end. In the restricted neck portion of the flask I place a thin ring of steel, tungsten or other metal, indicated at 3, and weld this ring to the flask as indicated. A yoke 5 is then inserted in the flask through 55 the bottom 4 thereof, which yoke has wound

there about the grid wire or electrode 6. The yoke also forms a support for the filament electrode 7. It will be seen that with this arrangement the grid electrode surrounds the filament but is insulated therefrom. The yoke 5 may be of any suitable material, but I have found that a solid glass yoke is satisfactory for the purpose. The leads of the filament pass through the yoke 5 out of the stopper 8, as shown at 9 60 and 10. The stopper 8 is preferably of glass and is forced into the neck formed by the thin metal plate or ring 3 while both the ring and stopper are hot to thereby secure an air tight joint. The yoke 5 is thus supported by the stopper 8. The grid wire 6 is sealed through the stopper as shown at 11. A metal bottom 12 for the flask is then welded to the open end 4 thereof, and the completely inclosed receptacle thus formed 70 is connected to a vacuum pump and is thereby exhausted of air through the tip 13 of the stopper 8, which is thereafter sealed as is well known in the glass blowing art.

It will be seen that I have provided an 80 exceedingly simple and strong structure of audion wherein the containing vessel forms one electrode of the audion as in this instance the flask 1 is the wing or plate electrode and is provided with a terminal 14. The problem of keeping the audion cool when in use is exceedingly simple in this type of audion in that the entire flask up to the stopper may be submerged in a cool- 85 ing fluid.

In Fig. 2 I show a modified structure of 90 metal audion wherein I dispense with the bottom 12, and the ring 3 and form the flask in one piece. In this arrangement, the open end of the flask 1 is narrowed or tapered as shown at 15 into a thin metal ring. The glass stopper 8 carrying the filament and grid electrodes is inserted as above described, in the end of the flask under heat, and the flask evacuated of air through the tip 13 which is thereafter sealed off. In this instance I prefer to employ nickel yokes 16 insulated from each other by a U shaped glass strip 17 to which is secured the filament 7.

While I have shown and described specific structures embodying my invention, I wish it to be understood that many arrangements and modifications will readily occur to those skilled in the art without departing 100 105 110

from the spirit of my invention or the scope thereof as defined in the claims. Therefore, what I claim as new and useful and of my own invention and desire to secure by Letters Patent is;—

1. The method of constructing a metal audion which consists in forcing a glass stopper under heat and carrying two electrodes, in a thin metal ring under heat and carried by a metal flask and finally exhausting the air from said flask.

2. The method of constructing a metal audion which consists of first welding a thin metal ring to one end of a metal flask, inserting through the other end of said flask an electrode bearing stopper, forcing said stopper into said thin ring while both said ring and said stopper are heated, welding an inclosing cap to the other end of the flask, and finally evacuating said flask of air through said stopper.

3. A metal audion comprising a metal receptacle open at one end, and provided with a neck portion of less thickness than the body of the receptacle, a glass stopper sealed to said thin neck portion and supporting two electrodes of the audion, the leads of said electrodes passing through said glass stopper.

4. An audion comprising an evacuated metal shell provided with a glass stopper forced while hot in the neck of said shell,

said stopper supporting two electrodes of said audion.

5. An audion comprising an evacuated metal shell provided with a glass stopper forced while hot in the neck of said shell, said stopper supporting two electrodes of said audion, said shell forming the third electrode of said audion.

6. An audion comprising an evacuated metal shell provided with a relatively thin neck, a glass stopper sealed to said neck, said glass stopper supporting two electrodes of said audion.

7. An audion comprising an evacuated metal shell provided with a restricted neck portion, a thin metal ring welded to said shell within said restricted neck portion, and a stopper sealed to said metal ring, said stopper supporting two electrodes of the audion.

8. An audion comprising an evacuated metal shell provided with a restricted neck portion, a thin metal ring welded to said shell within said restricted neck portion, and a stopper sealed to said metal ring, said stopper supporting two electrodes of the audion, and said shell forming the third electrode of said audion.

In testimony whereof I have hereunto set my hand on this 15th day of February A. D., 1917.

LEE DE FOREST.
